(57) **CLAIM**

The ornamental design for a protective placemat as shown and described.

DESCRIPTION

FIG. 1 is a perspective view of a protective placement of my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof; and,

FIG. 7 is a front elevation view thereof.

The line shading in the Figures is not surface ornamentation and forms no part of the claimed design.

1 Claim, 4 Drawing Sheets
